UNITED STATES PATENT OFFICE.

JOHN KLINGE, OF DUBUQUE, IOWA, ASSIGNOR TO SCHMID MANUFACTURING CO., OF DUBUQUE, IOWA, A COPARTNERSHIP COMPOSED OF E. C. SCHMID AND F. W. SCHMID.

ROTARY PUMP.

Application filed August 11, 1924. Serial No. 731,270.

This invention relates to a rotary force pump.

It is an object of this invention to provide a novel rotary force pump comprising a plurality of units having a common inlet and exhaust with branches leading to the different units and means for controlling the inlet and exhaust of each unit in order that one unit may not rob the other unit by either extracting the liquid therefrom or dissipating the vacuum or suction, and in preventing the liquid from slushing from one side to the other at the exhaust.

With these and other objects in view which will become more apparent in the following description and disclosures, this invention comprises the novel structure and combinations hereinafter described and more particularly pointed out and defined in the appended claims.

In the accompanying drawings which illustrate a preferred embodiment of this invention and in which similar reference numerals refer to similar features in the different views:

Figure 1 is a longitudinal sectional view through the rotary pump involving this invention.

Figure 2 is an enlarged sectional view upon the line 2-2 of Figure 1.

Figure 3 is a top plan view of the pump.

Figure 4 is a fragmentary sectional view through the driving shaft rotors and bearings.

Figure 5 is a sectional view substantially upon the line 5-5 of Figure 1.

Figures 6, 7 and 8 are views similar to Figure 5 but showing the rotor in different positions.

Referring now to the drawings there is shown a housing comprising two sections 1 and 2 secured together with a partition 3 between said sections. The outer end walls of the two sections are provided with aligned bearings 4 and 5 for journaling a shaft 6. Each housing section has a cylindrical chamber 7 concentric with the shaft 6. Above each chamber there is an extension 7' embodying a central slideway 8, and lateral inlet and outlet chambers 9 and 10. This construction of section 2 is clearly shown in Figures 5 to 8, the construction of section 1 being identical.

A cover 11 is secured over the top of the housing, and an inlet or fluid supply pipe

12, (Figure 3) having a forked end comprising the branches 12^a and 12^b which extend through the cover and respectively communicate with the intake passages 9 furnishes the means for conveying the fluid to the pump sections. An exhaust pipe 13 having a forked end comprising the branches 13^a and 13^b (Figure 3) which extend through the cover and communicate with the exhaust passages 10 furnishes the means for conducting the fluid from the pump.

Eccentrics 14 are secured upon the shaft 6, one eccentric is located in the chamber of each housing section. A rotor 15 is mounted upon each eccentric. Each rotor has an upwardly extending division plate 16 that is provided with a cylindrical head 17 that fits in a cylindrical bearing formed in the lower surface of a slide valve 18 which reciprocates in the slideway 8. The division plate 16 and slide valve 18 serve to divide each chamber into an intake compartment and an exhaust compartment.

Each sliding valve 18 also controls an inlet port 19 leading from the intake passage 9, and an exhaust port 20 leading into the exhaust passage 10. These ports are in the walls of the slideway 8. The valve 18 is provided with depending side flanges 21 that close these ports, and an oblique passage 22 that is adapted to register in a certain position with the exhaust port as shown in Figure 7.

In referring to Figure 1, it will be noted that when one eccentric 14 is at the bottom of its stroke, the other eccentric is at the upper limits of its throw, consequently the two pump units act alternately. In referring to Figures 5 to 8 it will be observed that when the intake port 19 is open the exhaust port 20 is closed, and that as the rotor travels around the inner periphery of its chamber, from this position the inlet port will be gradually closed and the exhaust port will be gradually opened. The closing of the inlet port will be completed when the rotor is at its lowest point as shown in Figure 7. When the rotor travels upwardly, the inlet port will be gradually opened and the exhaust port will gradually be closed.

In Figure 4, there is illustrated a novel method of lubricating such a pump. In referring to said figure it will be noted that the shaft 6 has a central duct 23 which ex-

tends from its outer end into the farther unit, ducts 24 extend from the duct 23 through the eccentrics to the inner peripheries of the rotors 15. A grease cup or oil can 5 25 is secured in the outer end of the duct 23 for supplying oil to the rotors. Centrifugal force will cause the oil to travel through the ducts 24 as is apparent.

It will be appreciated that this cutoff prevents the rotor of one unit when in downward action from robbing the other unit in either extracting the liquid therefrom or dissipating the vacuum or suction.

I am aware that many changes may be made, and numerous details of construction may be varied through a wide range, without departing from the principles of this invention, and I therefore do not purpose limiting the patent granted hereon otherwise than necessitated by the prior art.

I claim as my invention:

1. In a rotary pump, a housing comprising a pair of separable sections, an eccentric rotor in each section, an extension on each section embodying a central slideway and lateral inlet and outlet chambers, a division plate connected to the eccentric of each rotor, a right line sliding valve in each central slideway pivoted to its division plate and controlling ports communicating with said inlet and exit chambers, and common inlet and outlet pipes for said chambers.

2. In a rotary pump, a housing comprising a pair of separable sections, an eccentric rotor in each section, an extension on each section embodying a central slideway and lateral inlet and outlet chambers, a division plate connected to the eccentric of each rotor, a right line sliding valve in each central slideway pivoted to its division plate and

controlling ports communicating with said inlet and exit chambers, a single cover for said housing closing said slideway and inlet and outlet chambers, branch inlet and exhaust pipes on said cover communicating 45 with said inlet and exhaust chambers, and common inlet and exhaust pipes with which said branches communicate.

3. In a rotary pump, an eccentric rotor, a slide valve connected thereto and directly 50 controlling inlet and outlet ports, the position of said ports and of said valve being so related that the outlet port is open except at the very end of the exhaust cycle.

4. In a rotary pump provided with a 55 slideway, an eccentric rotor, a right line slide valve in said slideway connected to said rotor and having formed through it a passage to serve for fluid delivery, inlet and outlet ports being formed in the walls of said slide- 60 way, the passage in said valve and the outlet port being so positioned and inter-related that said outlet port is open except at the very end of the cycle of the rotor.

5. In a rotary pump provided with a 65 slideway having inlet and outlet ports in the walls thereof, an eccentric rotor, a right line slide valve adapted to reciprocate in said slideway and having a passage therethrough 70 to serve for fluid delivery, and a division plate connecting said rotor and said slide valve, said valve, passage and ports being so positioned and inter-related that at the end of the cycle of the rotor the inlet port is wide open and the outlet port entirely 75 closed.

In testimony whereof I have hereunto subscribed my name.

JOHN KLINGE.
